United States Patent Office.

EDWIN TAYLOR, OF TECUMSEH, MICHIGAN.

Letters Patent No. 81,438, dated August 25, 1868.

IMPROVEMENT IN STEAM-GENERATOR.

The Schedule referred to in these Letters Patent and making part of the same.

TO ALL WHOM IT MAY CONCERN:

Be it known that I, EDWIN TAYLOR, of Tecumseh, in the county of Lenawee, and State of Michigan, have invented a new and useful Improvement in Steam-Generators; and I do hereby declare the following to be a full, clear, and exact description of the same, reference being had to the accompanying drawings, which make part of this specification, and in which—

Figure 1 is a vertical longitudinal section of a steam-boiler and fire-box with my invention applied.

Figure 2 is a perspective view of the same.

Figure 3 is a plan of the boiler.

Figure 4 is a detached sectional view of the water-reservoir and its appendages.

Similar letters of reference indicate corresponding parts in the several figures.

The subject of this invention is a steam-generating apparatus in which the boiler is completely enclosed within the fire-box or furnace, so as to be entirely exposed to the fire at all parts, and in which the boiler is so suspended and combined with a counterbalance-weight or spring, that when the latter preponderates, in consequence of the reduced weight of the boiler caused by the evaporation of its contents, the motion thereby imparted to the boiler effects the opening of the valve through which water is supplied to the boiler from an elevated tank or reservoir.

In order that others skilled in the art to which my invention appertains may be enabled to fully understand and use the same, I will proceed to describe it in connection with the accompanying drawings.

A is the fire-box or furnace, and B the boiler enclosed therein. The boiler may in like manner be enclosed within brick-work, when desired. It will be seen that the boiler is exposed to the direct action of the fire on all sides as well as at the ends.

By thus arranging the boiler, the most economical and effective application of the heat is attained.

The boiler B is held in suspension by means of the chain C, the connection between the boiler and the chain being effected by means of the hook D and plate D', which plate connects the inner ends of the rods b b, the outer ends of said rods being clamped, bolted, or otherwise securely made fast to the boiler, as shown in fig. 3.

The chain C is attached to the end of a lever, E, which is mounted, so as to be capable of vibrating, upon a bridge or support, F, resting upon the top of the fire-box.

The lever E carries a weight, G, which serves as a counterbalance to the boiler B.

The weight G is hung at any desired point upon the lever E, by means of its bail, g, and the notches in the edge of the long arm of said lever. The notches may represent in inches the amount of water which the weight G is capable of counterbalancing at its several points of suspension. Thus the weight G, when adjusted at the extremity of the long arm of the lever E, will counterbalance the boiler when charged with a maximum supply of water, and to adapt said weight to counterbalance the boiler with a smaller quantity of water, it is adjusted nearer to the fulcrum of lever E.

The lever E has attached to its end a rod, H, whose upper end is attached to a lever, H', having a suitable supporting-fulcrum upon the elevated reservoir I, (see fig. 4.) The reservoir I may communicate with the boiler B through the flexible pipe-K and a rigid pipe, K', which latter rises from the boiler and through the fire-box, and is provided with a stop-cock, k. In the bottom of the reservoir I is a valve, J, which is attached to a tube J', passing centrally through it, and projecting above the water-line in the reservoir. The tube J' is connected to the lever H' by means of the rod h.

The smoke-stack or chimney is shown at L, and the steam-pipe of the boiler at M, the latter being provided with suitable guides, the better to steady and prevent from tilting the boiler B when in motion.

In order to an understanding of the operation, suppose the valve J to be closed, and the boiler, with a full supply, sustained by the weight G. Now, it is manifest that as the water evaporates, the boiler grows lighter, and as soon as it becomes incapable of counterbalancing the weight G, it is raised to a greater or less extent by the latter, and the consequent vibration of the lever E, and downward motion of the rod H, serve to lift the

valve J. A new supply of water is thereby admitted to the boiler B, which is thus depressed to its former position, in resuming which the boiler serves to close the valve J and cut off the water from the reservoir.

I am aware of no instance in which the boiler has been made to actuate the mechanism which opens and closes the channel which supplies it with water.

The tube J', projecting above the water-level in reservoir I, admits steam above the same, in order to equalize the pressure upon the opposite sides of the valve J, thus preventing the steam from opening the said valve.

is the supply-orifice of the reservoir, and 'a cock to try the depth of water therein. When water is being supplied to the reservoir I, the cock k of the feed-pipe K' is closed, but at other times it is left open.

It is manifest that a weight attached to a cord running over a pulley, or even a spring, or a combination thereof, might be made to perform the function of the parts G E C.

Having described my invention, what I claim as new herein, and desire to secure by Letters Patent, is—

The arrangement of the suspended counterbalanced boiler B within the fire-box or chamber A, and the elevated tank or reservoir I, substantially as and for the purpose set forth.

To the above I have signed my name, this tenth day of March, 1868.

EDWIN TAYLOR.
